UNITED STATES PATENT OFFICE.

ALFRED C. DODMAN, JR., OF SUMMIT, NEW JERSEY, AND CORA S. REIBER, OF NEW YORK, N. Y.; SAID REIBER ASSIGNOR TO SAID DODMAN.

DESIGN FOR CRETONNE.

Application filed March 26, 1924. Serial No. 9,069. Term of patent 14 years.

To all whom it may concern:

Be it known that we, ALFRED C. DODMAN, Jr., residing at 24 Oakridge Avenue, Summit, in the county of Union and State of New Jersey, and CORA S. REIBER, residing at 1544 Shakespeare Avenue, New York city, in the county of New York and State of New York, citizens of the United States, have invented a new, original, and ornamental Design for Cretonne, of which the

following is a specification, reference being had to the accompanying drawing, forming part thereof.

The figure is a plan view of a section of cretonne, showing our new design.

We claim:

The ornamental design for cretonne, as shown.

ALFRED C. DODMAN, JR.
CORA S. REIBER.
